US00D944620S

(12) **United States Design Patent** (10) **Patent No.:** **US D944,620 S**
(45) **Date of Patent:** **** Mar. 1, 2022**

(54) **DOOR HANDLE**

(71) Applicant: **Spectrum Brands, Inc.**, Middleton, WI (US)

(72) Inventors: **Yos Singtoroj**, Anaheim, CA (US); **Andy Chen**, Xiamen (CN)

(73) Assignee: **Spectrum Brands, Inc.**, Middleton, WI (US)

(**) Term: **15 Years**

(21) Appl. No.: **29/753,382**

(22) Filed: **Sep. 30, 2020**

(51) **LOC (13) Cl.** **08-06**

(52) **U.S. Cl.**

USPC **D8/308**

(57) **CLAIM**

The ornamental design for a door handle, as shown and described.

DESCRIPTION

FIG. 1 is a front perspective view of a door handle showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines depicting portions the door handle form no part of the claimed design.

1 Claim, 5 Drawing Sheets
